United States Patent

Des. 236,832
Patented Sept. 16, 1975

236,832

DENTAL FLOSS APPLICATOR

Wayne B. Jennings, 114 Cloverleaf Drive,
Athens, Ala. 35611

Filed Aug. 16, 1973, Ser. No. 388,758

Term of patent 14 years

Int. Cl. D24—99

U.S. Cl. D24—1 D

Fig. 1

Fig. 2

Fig. 3

FIG. 4

FIG. 5

FIG. 1 is a side elevational view of a dental floss applicator showing my new design, the side not shown being identical to the side shown;

FIG. 2 is a bottom plan view as seen along the line 2—2 of FIG. 1;

FIG. 3 is a top view as seen along the line 3—3 of FIG. 1;

FIG. 4 is a perspective view; and

FIG. 5 is a rear elevational view.

I claim:

The ornamental design for a dental floss applicator, as shown and described.
